UNITED STATES PATENT OFFICE.

THOMAS E. KAISER AND JONATHAN WILKINSON, OF OSHAWA, CANADA.

INVALID-BED.

SPECIFICATION forming part of Letters Patent No. 464,158, dated December 1, 1891.

Application filed April 30, 1891. Serial No. 391,063. (No model.) Patented in Canada January 28, 1891, No. 35,891.

To all whom it may concern:

Be it known that we, THOMAS E. KAISER and JONATHAN WILKINSON, subjects of the Queen of the United Kingdom of Great Britain and Ireland, residing in the town of Oshawa, in the county and Province of Ontario, and Dominion of Canada, have invented certain new and useful Improvements in Adjustable Invalid-Bed Appliances, (for which we have obtained a patent in Canada, No. 35,891, bearing date January 28, 1891,) of which the following is a specification.

Our invention relates to an improvement in invalid-beds, its object being to provide means to facilitate the nursing of persons helplessly sick, and to reduce the labor and danger in connection with the moving of sick persons to a minimum.

A further object is to construct the devices in such a manner that either or both ends or the sides of the bed may be elevated at will.

With these objects in view the invention consists in the combination, with a bedstead, of a movable bed located thereon, cords for suspending said movable bed, and adjustable clutches with which said cords are connected, whereby either or both ends or either side of the movable bed may be elevated.

The invention also consists in the combination, with a bedstead and a movable bed, of a revolute axle, adjustable clutches at each end of said axle connected with the movable bed and so constructed and arranged that by manipulating said clutches and rotating the shaft the movable bed may be elevated at either or both ends or either side.

The invention also consists in certain novel features of construction and combinations and arrangement of parts, as hereinafter set forth, and pointed out in the claim.

In the accompanying drawings, Figure 1 is a perspective side view of the adjustable invalid-bed appliance embodying the features of our invention. Fig. 2 is a perspective end view of the same. Figs. 3 and 4 are an end view and sectional view, respectively, of the revolving axle forming part of our invention.

In the drawings, A is a frame consisting of

two substantial upright wooden posts or columns securely joined together by girts at the top and bottom thereof. To the tops of said posts are affixed the brackets *a a*.

At the head of the bedstead a substantial wooden cross piece or beam B, which is attached to the posts at the head of the bed by straps or in any other secure manner, is placed, and from the said beam B and the brackets *a a* is suspended the movable canvas bed C, by means of the cords, hereinafter more particularly referred to. The beam B is provided with buffers of cork or other suitable material to prevent abrasion of the bedstead.

In hospital-beds and all bedsteads having low heads a substantial wooden frame similar in construction to the frame A is placed at the head of such bed, and from the brackets attached to said frame the head of the canvas bed C is suspended, the sheave-pulleys 1, attached to the lower part of the posts at the head of said bedstead, as hereinafter described, being attached to the bottom girt of the substituted frame. The canvas bed C is a rectangular wooden frame covered with strong canvas, having an aperture 2 in the center thereof and provided with four sheave-pulleys 3, one at each corner of said frame. The brackets *a a* are provided with two hooks 4, one to each bracket, and from each of these hooks is suspended a swivel sheave-pulley 5. There are two sheave-pulleys 6 attached to or suspended from the beam B. At the bottom of each of the posts at the head of the bedstead is fixed a sheave-pulley 1, and upon the bottom girt, which connects the two upright posts of the frame A, are fixed two sheave-pulleys 7.

It will be seen from the foregoing description that there are twelve pulleys employed in the lifting mechanism of the appliance.

In the frame A an iron axle D is placed at a height sufficient to allow the axle to operate free from the foot of the bed, the ends of the axle D revolving in journals bored into the posts of the said frame. The end of the axle D at the outside post of the frame A projects through its journal far enough to permit the attachment of the crank *d*. The axle

D is provided at its end next to the crank d with a ratchet-wheel e, and the pawl k is pivoted to one of the upright posts of the frame A, as shown in the drawings, Fig. 2, so that the canvas bed C may be securely maintained at any desired height. The axle D is also provided with two double iron clutches, one at each end of said axle. Each clutch is composed of three parts, F F' being the stationary parts, which are rigidly secured to axle D by set-screws, and E E' and G G' are the movable parts and are similarly perforated to loosely receive the axle D, so that it can freely revolve in the same. The parts E E' and G G' are provided with recesses, as shown in the drawings, Fig. 4, to receive the clutch-jaws I I', hereinafter referred to.

I I' are dovetailed iron clutch-jaws provided with thumb-pieces and so placed in recesses in the stationary parts F F' of the clutches as to slide into the corresponding recesses in the movable parts E E' and G G' when it is desired to throw any or all of the said movable parts in locking engagement with the axle D.

There are four ropes or cables required to operate the lifting mechanism of the appliance, and they are arranged in two pairs, one pair being on each side of the bed C, the said arrangement being more particularly described as follows, that is to say: Beginning with the ropes 10 on the side of the bed next to the crank d, one of the said ropes or cords, having been first knotted, is passed through the aperture in the clutch E, as shown in the drawings, (this being done before E is placed on the axle D.) The rope is then passed upwardly through an anti-friction pulley, as shown in the drawings, Fig. 1, to and through the pulley 5, attached to the bracket a, thence directly downward to and through the pulley 3 at the foot of the canvas bed C, thence upward to the bracket a, to which it is securely attached. The other rope on the same side of the bed—that is, the side next to the crank d—is, having been previously knotted, passed through the aperture in the clutch G, (this also being done before G is placed on the axle D.) The rope is then passed directly downward to and through one of the pulleys 7, attached to the bottom girt of the frame A, thence under the bed along the whole length thereof to and through the pulley 1, attached to the bottom part of the post at the corresponding side of the head of the bedstead, thence directly upward to and through the pulley 6, attached to the beam B, thence directly downward to and through the pulley 3, attached to the head of the canvas bed C, thence upward to the beam B, to which the rope is then securely attached. The ropes on the other side of the bed are placed in similar positions and follow similar courses, respectively.

The manner in which the several parts comprising our invention operate is as follows, that is to say: When it is desired to raise the

canvas bed C evenly, the operator will slide the clutch-jaws I I' into the recesses in the parts E E' and G G', the movable parts of the clutches, which by this device will then be thrown in locking engagement with the axle D. By the turning of the crank d the axle D turns the whole arrangement of clutches, so that all the ropes are brought into action, thus raising the bed C evenly at all points. To raise the head of the bed C, the operator will slide the clutch-jaws I into the recesses in G G', thus throwing the parts G G' in locking engagement with the axle D. The parts E E', not being locked with the said axle, will permit the same to revolve freely in E E'. The ropes attached to G G' are attached at their other ends to the pulleys at the head of the bed C. It will therefore be seen that, these ropes and no others being acted upon, the head of the bed C only will be raised. To raise the foot of the bed C, the operator will slide the clutch-jaws I' into the recesses in E E', thus throwing the parts E E' in locking engagement with the axle D. The parts G G', not being locked with the said axle, will permit the same to revolve freely in G G'. The ropes or cords attached to E E' are attached at their other ends to the pulleys at the foot of the bed C. It will therefore be seen that, these ropes and no others being acted upon, the foot of the bed C only will be raised. To raise the side of the bed C next to the crank d, the operator will slide the clutch-jaw I' into the recess in E and the clutch-jaw I into the recess in G, thus throwing the parts E G in locking engagement with the axle D. The parts E' G', not being locked with the said axle, will permit the same to revolve freely in E' G'. The ropes or cords attached to E G are attached at their other ends to the pulleys at the head and foot, respectively, of the canvas bed C on the same side. These ropes and no others being acted upon, the side of the canvas bed C next to the crank d only will be raised. To raise the other side of the canvas bed C, the parts E' G' will, by the manipulation of the clutch-jaws I I', be thrown in locking engagement with the axle D. The parts E G, not being locked with axle D, will permit the same to revolve freely in E G. The ropes or cords attached to the parts E' G' are attached at their other ends to the pulleys at the head and foot, respectively, on the same side. These ropes and no others being acted upon, the side of the canvas bed C to which these ropes are attached only will be raised. The lowering of the bed C is accomplished in all cases by raising the pawl k, thus releasing the ratchet-wheel e, and thereby allowing the axle D to revolve in the contrary direction until the lowering is accomplished.

What we claim as our invention, and desire to secure by Letters Patent, is—

The combination, with a bedstead, a mov-

able bed, and an adjustable frame, of an axle mounted on said frame, adjustable clutches carried by said axle, and cords carried by suitable pulleys, said cords being attached 5 to the movable bed and to said clutches, whereby either or both ends of the movable bed may be elevated and whereby either side

of said movable bed may be elevated, substantially as set forth.

T. E. KAISER.
JON. WILKINSON.
